(57) **CLAIM**

The design for anatomical support, as shown and described.

DESCRIPTION

FIG. 1 is a perspective elevational view of the anatomical support;

FIG. 2 is a left side elevational view of the anatomical support;

FIG. 3 is a right side elevational view of the anatomical support;

FIG. 4 is a front elevational view of the anatomical support;

FIG. 5 is a rear elevational view of the anatomical support;

FIG. 6 is a top elevational view of the anatomical support; and,

FIG. 7 is a bottom elevational view of the anatomical support.
